United States Patent Office

Des. 193,155
Patented July 3, 1962

193,155

NIGHT LIGHT

Robert Goldman and Lillian Goldman, Louisville, Ky.,
assignors to Lili, Inc., Salem, Ind., a corporation of
Indiana

Filed Aug. 18, 1961, Ser. No. 66,414

Term of patent 3½ years

(Cl. D48—20)

Fig. 1.

Fig. 3.

Fig. 2.

FIG. 1 is a front elevation view of our night light, showing our new design.

FIG. 2 is a rear elevation view thereof.

FIG. 3 is a fragmentary perspective view of one of the flower-like elements with the remaining portions of the light omitted for conveniences of illustration only.

We claim:

The ornamental design for a night light, as shown and described.
